UNITED STATES PATENT OFFICE.

CHARLES H. BUCHANAN, OF PHILADELPHIA, PENNSYLVANIA.

MANUFACTURE OF SHOES AND SLIPPERS.

SPECIFICATION forming part of Letters Patent No. 334,562, dated January 19, 1886.

Application filed October 22, 1885. Serial No. 180,604. (No model.)

To all whom it may concern:

Be it known that I, CHARLES H. BUCHANAN, a citizen of the United States, residing at Philadelphia, in the county of Philadelphia and State of Pennsylvania, have invented certain new and useful Improvements in the Manufacture of Shoes and Slippers; and I do hereby declare the following to be a full, clear, and exact description of the invention, reference being had to the accompanying drawings, which form part of this specification, in which—

Figure 1 is a plan of guide - strip of fine plaited material or straw-braid. Fig. 2 is a plan of same piece joined at heel, the material being a coarser plait or braid. Fig. 3 is a plan of an upper, same material as Fig. 2. Fig. 4 is a vertical section of shoe or slipper embodying my improvement. Fig. 5 is a perspective of article shown in Fig. 4. Fig. 6 is a plan of upper in which the successive courses of overlapping material are separate strips.

My invention has for its object to provide a new kind, style, or form of shoe or slipper—viz., one the upper of which shall be composed of strands, strips, or lengths of narrow material united in such manner as to overlap each other and give the desired or necessary shape or contour to the upper.

A further object of my invention is to provide a method or process of construction of a shoe or slipper upper of the kind mentioned, which may be practiced on or put into effect by means of a sewing-machine, whereby such uppers can be produced with facility and comparatively slight expense.

My invention consists, first, in the new product herein mentioned—viz., a shoe or slipper upper composed of a guide strip or band having stitched thereto strips or narrow pieces of material united in overlapping strands; second, in the process or method of constructing or producing a shoe or slipper upper having the characteristics mentioned; and, third, in certain details of construction and of methods hereinafter fully specified and claimed.

Any suitable material in the form of a long narrow strip, such as tape or ribbon, may be used in producing the upper of my invention; but the article mainly intended for use by me is straw - braid, either natural or imitation

straw or grass, or both natural and imitation straw-braid. In forming an upper of this material I first take a strip or piece of it of sufficient length to encircle a foot slightly below the ankle, or a last a short distance below the top or horizontally around the instep and heel. In the accompanying drawings, A represents this piece, which I call the "guide-strip," as it forms the foundation or initial piece of the upper. I place this strip A on a sewing-machine and run a line of stitching, a, around its inner edge, and impart to the strip at or about its middle a curve or "flare," a', which said inner line of stitching holds securely and firmly in a horizontal or approximately horizontal plane. This flare forms the beginning of the toe or instep curve of the upper. The two ends of the strip are united at a' to form the heel, and in such way that the heel portion is in a plane at or about at right angles to the toe or instep portion; or, while the latter is horizontal, or approximately so, the heel part is vertical or substantially vertical. Said ends of the guide-piece may be united when the line of stitching a is formed, or subsequently. The piece A is then an endless band, having two curves, one at the instep or toe portion and one at the heel, the front curve being flat or horizontal and the rear curve vertical, said front curve being secured by the line of stitching a on or near the inner edge of the strip. I next take a long strip of material, B—such as straw-braid—and attach a course of it to the piece A, underlapping said piece and sewing to the outer edge of the latter at b, and, the work being done on a suitable sewing-machine, the line of stitching being run in the reverse direction from the line a. The strip B is then continued on in overlapping courses C C', &c., all of said courses, including the first, having the flat or nearly flat curve at the toe or instep similar to that of the piece A, and the turn at the heel like the latter, said front curves being secured by "flaring" and said heel-turn being produced by "drawing" the material in the act of stitching. (By flaring is meant bending or swaying the material laterally while sewing, and by drawing is meant holding tightly or producing tension in the

under course while stitching to the one above.) These courses are continued until a complete upper is produced, and said upper is afterward secured to a sole, D, composed of leather or other material, in the same manner as leather or other uppers usually are.

Instead of making the upper of a guide-strip, A, united at its ends to form an endless band, and a single long strip, B, forming 10 courses or overlapping strands, as shown in Figs. 1, 4, and 5 of the drawings, the guide-strip A, having the front curve, a', produced by an inner line of stitching, a, may have its ends not united, and successive pieces of the same 15 shape may be stitched to it for forming overlapping courses of varying and gradually increasing length with the toe or instep curvature. This will produce an upper like that shown in Fig. 6, A' being the guide-strip, B' 20 the next course, and C' the successive courses stitched together at their outer or overlapping edges and open at the heel. The heel of this upper may be formed like that of an ordinary leather upper—viz., by stitching the heel ends 25 of the upper together and to a transverse or vertical strip or stay.

I do not herein broadly claim a shoe or slipper upper, or a shoe or slipper the upper of which is composed of strands or strips of material united to each other in overlapping courses, as the same is claimed in another pending application of mine for Letters Patent—viz., my application filed August 7, 1885, No. 173,861, my claims herein being confined 35 to a construction and method involving the foundation-piece hereinbefore described.

What I claim as my invention is as follows:

1. A shoe or slipper upper composed of a guide-strip or band, A, having the outline of 40 the top of the shoe produced by a line of stitching on or near its inner edge, which secures

said configuration, and overlapping courses of material secured to said guide-strip and to each other, substantially as shown and described.

45

2. The process herein described of forming uppers for shoes or slippers from straw-braid or other material in strips or lengths, said process consisting in first stitching a strip to form a band or guide of the general configuration of the top of the shoe, and then stitching successive strands or pieces thereto, said strands overlapping each other at the edges, substantially as shown and described.

50

3. The process herein described of forming an upper of a shoe or slipper, said process consisting of the following steps: first, forming a guide-strip or foundation-piece of a strip of material curved at or about its middle by stitching it along its inner edge and flaring it 60 while so stitching it and fastening the ends of said strip together; second, securing to said foundation-piece a strip of long narrow material by uniting it to the outer edge of the foundation-piece by a line of stitching run in 65 the direction opposite to that of the inner line of stitching; and, third, stitching successive courses of the second strip to each other, each inner course overlapping the one outside, and all the courses having a front curve and a rear 70 curve similar to those of the guide-strip, said front curve being produced by flaring and said rear curve by drawing in the act of stitching them together, substantially as set forth.

In testimony that I claim the foregoing I 75 have hereunto set my hand, this 8th day of October, 1885.

CHAS. II. BUCHANAN.
